RUDOLF SEIDL, OF MINNEAPOLIS, MINNESOTA.

TOY SUBMARINE.

1,306,284.

Specification of Letters Patent. Patented June 10, 1919.

Application filed April 6, 1917. Serial No. 160,162.

To all whom it may concern:

Be it known that I, RUDOLF SEIDL, a citizen of the United States, residing at Minneapolis, in the county of Hennepin and State of Minnesota, have invented certain new and useful Improvements in Toy Submarines, of which the following is a specification.

The invention has for its object the provision in a toy boat of simple, inexpensive, efficient mechanism so arranged and operated as to cause the boat to navigate upon and beneath the surface of a body of water, successively diving and rising and at times running on an even keel both afloat and submerged.

A preferred embodiment of the invention is set forth in the accompanying drawing and described in detail in that portion of the specification following. However, the invention is obviously susceptible of embodiment in varied constructional forms without departure from the essence thereof as set forth in the appended claims, wherefore the drawing and description are to be taken in an illustrative and not in an unnecessarily limiting sense. In the drawings—

Figure 1 is a partial vertical longitudinal section through a toy submarine embodying the invention; and

Fig. 2 is a top plan view of the same.

Having reference to the drawings, the hull of the boat is indicated at 11, chambered out at 12 to receive the operating mechanism access to which is given through the opening 13 closed by the cork stopper 14. In order to provide for stability the weight of the mechanism is naturally below a median line, additional weight along the keel being provided at 15 and 16, while a conning tower 17 is provided having an interior of cork or other lighter material. An upper fin 19 is also arranged longitudinally of the upper surface of the hull while thin metal fins 20 are arranged beneath the stern on each side of the propeller. As an additional embellishment a periscope 21 may be provided as also a flag staff 22.

For convenience in manufacture and assembly the device is here shown as having the hull constituted of a central cylindrical open-ended portion 23 with a forward wood portion 24 fitted into the metal cylinder, while aft a wooden portion 25 is joined to the closed end of the cylinder.

Within the chamber 12 is disposed a col-

lapsible rubber ball 26 the interior of which has unobstructed communication with the exterior of the hull below the water line through a channel 27 forwardly projecting. In the after portion of the chamber 12 is mounted the clock mechanism including a winding arbor 28 accessible through the opening 13, the spring 29, the crank shaft 30, and the train of gearing ending in the pinion 31 fixed upon the propeller shaft 32, all of the parts being supported in suitable bearings. To the crank portion of the shaft 30 is connected a plunger rod 33 bearing upon its forward end the plunger head 34 which in the retracted position bears against the surface of the expanded ball 26 and which serves as the crank shaft moves through 180 degrees to collapse the ball 26. Fixed upon the plunger rod 33 at 35 are a pair of wires 36 rearwardly extending and joined at their rear ends by a transversely arranged weight 37.

Although the shaft 32 of the propeller 38 may fit snugly within its journal or suitable stuffing boxes may be provided, yet to simplify the construction and provide for the discharge of water entering through the bearings, a drain port 39 is advantageously provided in the bilge and closed by the stopper 40. At intervals, the boat may be removed from the water and the stopper 40 taken out permitting any water within the hull to be discharged at 39.

In operation, the clock mechanism having been wound through the opening 13, the stopper 14 is placed in position sealing the hull against the entrance of water when submerged. With the parts in the position shown in Fig. 1, the boat will float upon the surface until the plunger head 34 moves forward to the extreme limit of its stroke and begins its rearward movement whereupon water is drawn in through the channel 27 to the interior of the bulb or ball 26 thus increasing the specific gravity of the boat and causing the same to settle lower in the water. The filling of the bulb 26 will cause the bow of the boat to incline downward by reason of the body of water within the bulb being slightly forward of the center of gravity, and as the boat is moving forward under the impetus of the propeller 38 the boat will dive at a gentle inclination.

It will be observed that as the plunger head 34 moves to the rear, the weight 37 likewise moves to the rear, thus compensat-

ing for the additional weight of water in the bulb 26, the weight 37 being moved aft of the center of gravity to a greater or less distance corresponding to the amount of water 5 taken into the bulb 26. The shifting of this counterweight 37 is slightly disproportionate to the amount of water taken into the bulb 26, so that during the time that the bulb is filling there will be a slight preponderance of weight forward of the center of 10 gravity and when the same is completely filled there will be a slight preponderance of weight aft of the center of gravity, whereby the prow of the boat will be tilted downward when diving and upward when 15 rising.

After the plunger head 34 has moved to the extreme rear limit of its stroke, the direction of movement is reversed and it progressively collapses the bulb 26 expelling the water therefrom through the channels 20 27, decreasing the specific gravity of the boat and causing the same to rise to the surface.

25 It will be observed that a very inexpensive construction is provided, closely simulating a submarine in its appearance and action, the boat successively traveling upon the surface and below the surface of the water, 30 diving and rising a number of times with one winding of the spring.

I claim:

1. In a device of the class described, the combination of a hull having an interior 35 chamber, a collapsible container therein having a channel communicating with the exterior below the water line, a propeller, and mechanism for driving the propeller and alternately collapsing and expanding the 40 container whereby to alter the specific gravity of the hull.

2. In a device of the class described, the combination of a hull having an interior 45 chamber, a collapsible container therein having a channel communicating with the exterior below the water line, a propeller, and mechanism for driving the propeller and alternately collapsing and expanding the 50 container whereby to alter the specific gravity of the hull, said container being off the center of gravity of the laden hull, a counterweight at the opposite side of the center of gravity and shiftable by the said mechanism in the act of collapsing and expanding the 55 container to compensate therefor.

3. In a device of the class described, the combination of a hull having an interior 60 chamber, a collapsible container therein having a channel communicating with the exterior below the water line, a propeller, and mechanism for driving the propeller and alternately collapsing and expanding the 65 container whereby to alter the specific gravity of the hull, said container being off the center of gravity of the laden hull, a counter-

weight at the opposite side of the center of gravity and shiftable by the said mechanism in the act of collapsing and expanding the container to compensate therefor, the shifting of the counterweight being slightly disproportionate to the changes in the container whereby to tilt the prow downward when diving and upward when rising. 70

4. In a device of the class described, the combination of a hull having an interior 75 chamber, a collapsible container therein having a channel communicating with the exterior below the water line, a propeller, and mechanism for driving the propeller and alternately collapsing and expanding the container whereby to alter the specific gravity of the hull, said mechanism including a plunger arranged to act on the container to alternately discharge the contents thereof and to permit the same to fill upon the reversal of its stroke. 80

5. In a device of the class described, the combination of a sealed hull having an interior chamber, a collapsible rubber bulb 90 therein having a pipe leading to the lower exterior portion thereof below the water line, a propeller, a plunger arranged to act on the bulb to collapse the same and thereafter to permit it to expand, and clock mechanism to drive the propeller and to 95 periodically press the plunger against the bulb.

6. In a device of the class described, the combination of a sealed hull having an interior chamber, a collapsible rubber bulb 100 therein having a pipe leading to the lower exterior portion thereof below the water line, a propeller, a plunger arranged to act on the bulb to collapse the same and thereafter to permit it to expand, and clock 105 mechanism to drive the propeller and to periodically press the plunger against the bulb, and a counterweight shiftable by the clock mechanism forward and aft to compensate for the change of the center of gravity due to the collapsing and expanding of the bulb. 110

7. In a device of the class described, the combination of a sealed hull having an interior chamber, a collapsible rubber bulb 115 therein having a pipe leading to the lower exterior portion thereof below the water line, a propeller, a plunger arranged to act on the bulb to collapse the same and thereafter to permit it to expand, and clock mechanism to drive the propeller and to periodically press the plunger against the bulb, and a counterweight shiftable by the clock mechanism forward and aft to compensate for the change of the center of gravity due to the 120 collapsing and expanding of the bulb, the shifting of the counterweight being slightly disproportionate to the center of gravity whereby to tilt the prow downward when diving and upward when rising. 125

8. In a device of the class described, the combination of a hull having an interior chamber, a collapsible rubber bulb therein having a pipe leading to the exterior portion thereof below the water line, clock mechanism including a spring, a winding arbor, a train of gears, and a crank shaft, a propeller driven by the gears, a plunger rod connected to the crank shaft, a plunger head 10 on the rod and arranged to bear on the bulb and on its forward stroke to collapse the bulb and upon its return stroke to permit the bulb to expand.

9. In a device of the class described, the combination of a hull having an interior chamber, means therein to vary the specific gravity of the laden hull, a propeller, and clock mechanism for driving the propeller and for varying the specific gravity of the 15 hull below and above the critical point "1" whereby to cause the same to successively submerge and emerge.

10. In a device of the class described, the combination of a hull having an interior chamber, collapsible and expansible means therein to vary the specific gravity of the laden hull, a propeller, and clock mechanism for driving the propeller and for varying the specific gravity of the hull below and 20 above the critical point "1" whereby to cause the same to successively submerge and emerge.

11. In a device of the class described, the combination of a hull having an interior chamber, collapsible and expansible means therein to vary the specific gravity of the laden hull, a propeller, and clock mechanism for driving the propeller and for varying the specific gravity, the hull having a 25 30 35 connecting tower of relatively light material to maintain stability.

12. In a device of the class described, the combination of a hull having an interior chamber, means therein to vary the specific gravity of the laden hull, below and above the critical point "1" whereby to cause the same successively to submerge and emerge, a propeller, and clock mechanism for driving the propeller and for varying the specific 40 45 50 gravity, the hull having an upper opening affording access to the clock mechanism, and a closure stopper for said opening.

13. In a device of the class described, the combination of a hull having an interior chamber, means therein to vary the specific gravity of the laden hull, below and above the critical point "1" whereby to cause the same successively to submerge and emerge, a propeller, and clock mechanism for driving the propeller and for varying the specific 55 60 65 gravity, and a drain port in the bilge, and a closure therefor.

14. In a device of the class described, the combination of a hull having an interior chamber, collapsible and expansible means 65 therein to vary the specific gravity of the laden hull, a propeller, and clock mechanism for driving the propeller and for varying the specific gravity, the hull having a connecting tower of relatively light material to 70 maintain stability and an upper opening affording access to the clock mechanism, a closure for said opening, a drain port in the bilge, and a closure therefor.

15. A toy submarine embodying a hull, 75 continuously operating power driven means for varying the specific gravity of the hull whereby to cause the same periodically to sink and rise.

16. A toy submarine embodying a hull, 80 continuously operating power driven means for varying the specific gravity of the hull whereby to cause the same periodically to sink and rise, and mechanical means acting to depress and elevate slightly the forward 85 end of the hull according as the same is sinking or rising.

17. A toy submarine embodying a hull, continuously operating power driven means for varying the specific gravity of the hull 90 whereby to cause the same periodically to sink and rise, and means periodically to shift the center of gravity of the hull longitudinally thereof to depress and elevate slightly the forward end of the hull according as the 95 same is sinking or rising.

In witness whereof I have hereunto signed my name in the presence of two subscribing witnesses.

RUDOLF SEIDL.
